FIG. 1

The dominant feature of my design resides in the shape of the legs shown in full solid lines on the drawing. This comprises the progressively deeper flutings in the outer surface or surfaces of the leg beginning at a point near the top of the leg and progressing to near the bottom thereof below which the peripheral shape of the leg is rapidly restored to its initial or upper shape.

I claim:

The ornamental design for a chair, as shown.
